UNITED STATES PATENT OFFICE.

ROBERT J. O. SIMPSON, OF ATHOL, MASSACHUSETTS, ASSIGNOR TO THE L. S. STARRETT COMPANY, OF ATHOL, MASSACHUSETTS, A CORPORATION OF MASSACHUSETTS.

DESIGN FOR A MEASURING TAPE.

Application filed April 8, 1926. Serial No. 17,221. Term of patent 14 years.

To all whom it may concern:

Be it known that I, ROBERT J. O. SIMPSON, a citizen of the United States, residing at Athol, in the county of Worcester, Commonwealth of Massachusetts, have invented a new, original, and ornamental Design for Measuring Tapes, of which the following is a specification, reference being had to the ac-

companying drawings, forming part thereof.

Fig. 1 is a face view of a tape showing my new design, and

Fig. 2 is an edge view thereof.

I claim:

The ornamental design for a measuring tape, as shown.

ROBERT J. O. SIMPSON.
